UNITED STATES PATENT OFFICE.

EDWARD P. HUMMEL, OF STERLING, COLORADO.

LOCK SWITCH.

Application filed October 3, 1924. Serial No. 741,480.

This invention relates to a locking switch that has for its primary object the construction of a combination lock wherein it is including a switch structure that can only 5 be moved to a closed position under predetermined position of the parts of the combination lock. An object of the invention is the construction of a switch that may be opened and closed only by the person knowing the combination of the lock. Besides 10 the above my invention is distinguished in the novel, substantial manner in which the parts are constructed and associated.

With these and other objects in view the 15 invention will be better understood from the following description taken in connection with the accompanying drawing, wherein:

Fig. 1 is a vertical sectional view of the 20 lock,

Fig. 2 is a top plan view of the dial member,

Fig. 3 is a sectional view on the line 3—3 25 of Fig. 1,

Fig. 4 is a sectional view on the line 4—4 30 of Fig. 1,

Fig. 5 is a sectional view thru the base,

Fig. 6 is a plan view of the main disc,

Fig. 7 is a plan view of the auxiliary disc 35 and

Fig. 8 is a plan view of one of the lock washers.

Again referring to the drawings illustrating one of the many constructions of my 35 invention, the numeral 1 designates a base of insulating material secured to the casting 2 by the bolts 3. This base carries the usual stationary contacts 4 to co-operate with the switch blade 5 secured to a stem 6 as indicated at 7. This stem has one end 40 mounted in the base while the upper end projects externally of a housing 8 and has attached thereto a knob 9. A sleeve 10 is arranged around the stem 6 and has an arm 45 11 that is provided with a lug 12 seated in a hole in a base plate 13 that is in turn held against turning movement in any suitable manner.

Mounted upon this sleeve 10 is a plurality 50 of tumblers hereinafter known as main tumbler discs 14. By referring to Fig. 6, it will be seen that the main disc is provided with a plurality of holes 16 adapted to have a changeable connection with pins 17 carried by the auxiliary disc 15. The discs are provided with co-acting lugs 18 brought

into engagement with each other in the turning of the disc. The main discs 14 are further provided with recesses 19 which are brought into alignment with each other in 60 predetermined position with all the discs so as to allow the manipulation of the switch structure hereinafter described.

Lock washers 21 engage the sleeve and 65 properly space the discs. Collar 22 is rotatably mounted upon the stem and a portion of the sleeve and it carries a single lug 23 and this collar 22 is rigidly secured to the dial member 24 by the screw 25, which has interchangeable connection with the plurality of holes in the collar 22 so as to allow changing of the combination.

The switch blade 5 is provided with a pin 26 passing thru an arcuate slot 27 in the base plate and having pivotal connection 70 with the link connection 28. This link connection comprises a pair of links 29 and 30, the latter pivoted to the base plate as indicated at 31 and further carries a pin 32 so positioned as to be held against movement by the disc except when the disc has been properly moved to bring the recesses into alignment in which position the pin 32 is free to move into the recesses for allowing 80 movement of the switch blade to a closed position. To complete the invention the usual electric wires 33 are connected to the stationary contacts.

From the foregoing description taken in 90 connection with the accompanying drawings, it will be apparent that by properly shifting and positioning the tumbler discs and by manipulating the dial 24 the recesses will be brought into alignment to allow the switch to be closed by manipulating the knob 9. Whenever the combination is to be changed it is only necessary to disassemble 95 the discs and change their relative relations to each other.

Of course, it is to be understood that the 100 tumbler construction may be designed in various other manners and various other switch structures may be used in the combination and, therefore, I do not desire to be limited in any manner except as set forth in the claims hereunto appended.

Having thus described my invention, what I claim is:

1. A switch lock including a base plate, a 110 movable switch blade, a locking pin, a member pivotally carried by the base plate and supporting the locking pin and having op-

erative connection with the switch blade, an operating member for the switch blade, locking means for the switch blade including a plurality of members adapted for engagement with the locking pin to prevent operation of the operating member to move the switch blade and having recesses formed therein normally out of registration with respect to each other but movable into registration to receive the locking pin to permit operation of the operating member, and means for moving the members to bring the recesses into registration.

2. A switch lock including a base plate provided with an arcuate recess concentric with the center thereof, a plurality of rotatable discs having recesses formed therein normally out of registration with respect to each other and adapted for registration under certain conditions, means for rotating the discs to bring the recesses into registration with respect to each other, and a switch structure including a switch blade, an operating member for the switch blade, a guide member for the switch blade adapted to work in the arcuate recess, a movable locking member for the switch blade, and a connection between the locking member and the guiding member permitting movement of the locking member into the recesses when in registration with respect to each other and upon operation of the operating member.

3. A switch lock including a base plate provided with an arcuate recess concentric with the center thereof, a switch structure including a switch blade, an operating member for the switch blade, a guide member

for the switch blade adapted to work in the arcuate recess, a movable locking member for the switch blade, a connection between the locking member and the guide member permitting movement of the locking member upon operation of the operating member, and locking mechanism including recessed members normally preventing operation of the operating member but movable to permit movement of the locking member into the recesses thereof to permit operation of the operating member to operate the switch blade.

4. A switch lock comprising a housing, a sleeve within the housing, a plurality of main tumbler discs mounted on the sleeve having recesses formed therein, a plurality of auxiliary tumbler discs mounted on the sleeve and adapted to have adjustable connection with the main discs, lugs on all of the discs adapted for engagement with each other at predetermined positions of the disc, a dial member for giving movement to the discs, an operating knob positioned at the top of the dial member, a stem projecting from the operating knob through the sleeve, and connected for operation with the operating knob, a switch blade mounted on the stem, contact elements associated therewith, a pin adapted for movement within the recesses when in registration with respect to each other, and a link connection between the pin and the switch blade permitting operation of the pin upon operation of the stem.

In testimony whereof I affix my signature.

EDWARD P. HUMMEL.
